DESIGN FOR A COVER OR DUST-CAP FOR TIRE-VALVES.

No. 38,675.

Specification for Design.

Patented July 9, 1907.

Application filed January 31, 1905. Serial No. 243,585. Term of patent 14 years.

To all whom it may concern:

Be it known that we, MAXIMILIAN CHARLES SCHWEINERT, residing at West Hoboken, in the county of Hudson and State of New Jersey, and HENRY P. KRAFT, residing in the city, county, and State of New York, both citizens of the United States, have jointly invented a new, original, and ornamental Design for a Cover or Dust-Cap for Tire-Valves, of which the following is a specification, reference being had to the accompanying drawing, forming part thereof.

The figure of the drawing is an elevation of a cover or dust cap made according to our new design.

We claim,—

The ornamental design for a cover or dust cap for tire valves as shown.

MAXIMILIAN CHARLES SCHWEINERT.
HENRY P. KRAFT.
